C. H. BRAINARD,

TARGET APPARATUS.

APPLICATION FILED APR. 12, 1918.

1,286,215.

Patented Dec. 3, 1918.

UNITED STATES PATENT OFFICE.

CLARENCE H. BRAINARD, OF ALBANY, NEW YORK.

TARGET APPARATUS.

1,286,215.

Specification of Letters Patent.

Patented Dec. 3, 1918.

Application filed April 12, 1918. Serial No. 228,133.

To all whom it may concern:

Be it known that I, CLARENCE H. BRAINARD, a citizen of the United States, residing at Albany, in the county of Albany, State 5 of New York, have invented certain new and useful Improvements in Target Apparatus; and I do hereby declare the following to be a full, clear, and exact description of the invention, such as will enable others 10 skilled in the art to which it appertains to make and use the same.

The present invention relates to target apparatus and particularly to a sectional target preferably associated with means for 15 indicating at a desired place or places the relative position of the section struck by the bullet or other missile.

The object of the invention is to provide 20 apparatus of this kind capable of using a target of any desired form or contour, set at any desired angle or position for receiving bullets or other kinds of missiles from the front or above. The target has a plurality of open-ended receiving pockets with converging walls, and a plurality of plungers 25 in registry with the rear or small openings, the pockets having any desired shape or arrangement to correspond with army standards, or otherwise. If desired, the indicating 30 mechanism may be actuated by the movement of the plungers to indicate the relative position on the target of the particular plunger struck by a bullet, and a bullet receptacle in communication with the pockets may be provided to collect the bullets as 35 they fall from the plungers.

Preferably, each plunger has an angularly-divergent impact face pressed over the rear open end of the pocket by a spring capable 40 of absorbing substantially all the kinetic energy of the moving bullet upon impact with the plunger. By sloping the impact face rearwardly and downwardly, the bullets drop without substantial force 45 into the bullet receptacle. At the same time the movement of the plunger against the spring may be utilized to actuate the indicator as by closing a switch arranged in the path of the moving plunger and electrically connected in the circuit with one or 50 more annunciations.

Whether or not the indicating mechanism or the bullet receptacle is used, my invention comprehends the provision in a sectional 55 target of a plurality of shock absorbing plungers each having a spring tending to

hold the impact face seated in registry with the rear opening of the pocket and associated with compressible material arranged to assist in stopping the moving plunger 60 upon excessive impact.

In the accompanying drawings illustrating the preferred form of my invention,

Figure 1 is a vertical elevation, partly in section, of the target; and Fig. 2 shows the 65 target and an indicator in front elevation, and illustrates diagrammatically the electrical connections between them.

The target 1 is supported from a firmly set base 2 by means of the cradle members 3. 70 The base of the target is made up of a plurality of metal bullet-receiving pockets 4 in any suitable arrangement, each pocket having converging walls 5 leading from a large opening 6 at the front to a small opening 7 75 at the rear. No matter what form or arrangement the pockets may have to correspond with targets of army standards or otherwise, the front of each separating wall is provided around its entire periphery with 80 sharp-edged hardened steel strips 8 capable of withstanding impact of shell-fired bullets without damage and providing sharply-defined dividing lines between adjacent pockets, so that a bullet is caught by one pocket 85 or another no matter where it may strike the target.

Each pocket 4 is provided with a plunger adapted to absorb the shock of impact, to deflect the bullet into a collecting receptacle, 90 and to actuate the indicating mechanism. Each plunger has an impact member 9 with a partial rim normally seated by the coil spring 26 against the rear faces of the pocket walls, as shown, and an angularly-divergent 95 impact face 10 in registry with the rear opening 7 of the pocket. The impact face slopes rearwardly and downwardly in such manner that substantially all the kinetic energy of the moving bullet is absorbed upon 100 impact before the bullet is deflected downwardly. The impact member is mounted on the rod 11 which is journaled through the connecting wall 12 and also through a rigidly secured bearing block 13 having a cup-shaped cavity at 14. In this cavity is arranged a collar 15 fastened on the rod, and a rubber pad or stop 16 adapted to engage the collar upon excessive movement of the rod due to unusually severe impact.

The bullet receptacle 17 communicates through openings 18 with all the pockets, so

that all of the bullets striking the target are collected there and may be removed at any time through a suitably arranged door.

The indicating mechanism includes one or 5 more indicators of annunciator form like that shown at 19 in Fig. 2. The face of each annunciator is sectionalized like the target and each section is provided with a drop 20 corresponding with the similarly located 10 pocket of the target. Behind each plunger there is arranged an electric switch 21 having an upwardly projecting push button 22 in the path of movement of the rod 11. The rear end of this rod is beveled as shown at 23 15 so as to reliably engage the switch contacts and thereby close the electrical circuit formed by the wires 24, the battery or other source of electric current 25, and the annunciator magnet controlling the corresponding drop.

It will be observed that the converging walls of the pockets are necessarily met at an acute angle by a bullet fired at the target from any point, and that by suitable modification in a manner known to those skilled 25 in the art, the target may be readily adapted for use with bullets or missiles fired or dropped from above.

What I claim is:

30 1. In target apparatus, a sectional target having a plurality of open-ended receiving pockets with converging walls, a plurality of shock absorbing plungers each registering with the rear opening of a pocket and having 35 an angularly-divergent bullet-deflecting impact face, a bullet receptacle in communication with said pockets to receive the bullets deflected from the impact face of the plungers, and means for indicating the relative position of the plunger moved by impact.

2. In target apparatus, a sectional target

having a plurality of open-ended receiving pockets with converging walls, a plurality of impact-actuated plungers each having a 45 downwardly and rearwardly sloping bullet-deflecting impact face registering with the rear opening of a pocket to deflect a bullet downwardly, a bullet receptacle in communication with said pockets to receive the bullets deflected from the impact face of the plungers, and means for indicating the relative position of the plunger moved by impact.

3. In target apparatus, a sectional target 55 having a plurality of open-ended receiving pockets with converging walls, a plurality of plungers each having an impact face at its front end in registry with the rear opening of a pocket and a beveled actuating face at 60 its rear end, a plurality of electrical switches each arranged in the path of the beveled face of a plunger to be actuated upon movement thereof, and an indicator electrically connected to said switches to indicate the relative position of the plunger moved by impact.

4. In target apparatus; a sectional target having a plurality of open-ended receiving pockets with converging walls; and for each 70 pocket a shock absorbing plunger comprising an impact receiving member, a rod supporting said member, a rigid bearing block having a bearing through which said rod is arranged to slide and having a cup-shaped 75 cavity, a collar fastened on said rod and located within said cavity, a spring holding the impact member seated in registry with the rear opening of the bullet-receiving pocket, and compressible material arranged 80 in the cup-shaped cavity to engage said collar upon excessive movement of the plunger.

In testimony whereof I affix my signature.
CLARENCE H. BRAINARD.
